UNITED STATES PATENT OFFICE

ROBERT E. EINSTEIN, OF ST. LOUIS, MISSOURI, ASSIGNOR TO ST. LOUIS FROG & SWITCH COMPANY, OF ST. LOUIS, MISSOURI, A CORPORATION OF MISSOURI

RAILROAD CROSSING

Application filed August 29, 1928. Serial No. 302,791.

This invention relates to railroad crossings of the type that are constructed of cast metal.

One object of the invention is to provide a cast metal railroad crossing that has greater flexibility than the conventional cast metal railroad crossings now in general use.

Another object is to provide a cast metal railroad crossing that is not only stronger and more reliable than a one-piece cast metal crossing, but it is easier to manufacture and capable of being produced at a lower cost.

And still another object of my invention is to provide a built-up cast metal railroad crossing that is easy to assemble and whose component parts are of such design that separate tie plates and braces are not required to mount and anchor the crossing on the track ties on which it rests.

To this end I have devised a railroad crossing that is composed of a plurality of cast metal members detachably combined with each other in such a way as to produce a structure that is more flexible than the conventional one-piece cast metal crossing whose intersecting portions are solid and present a rigid body of metal to the impact of the wheels in running over the flangeway openings of the crossing.

By constructing the crossing in this manner I not only reduce wear and impact, both on the crossing and on the wheels that travel over the same, but I also simplify the operation of constructing the crossing and reduce the cost of manufacturing the same, due to the fact that the crossing is built up of a plurality of units of simple design that can be cast easily with a relatively low percentage of breakage and rejects, and which require relatively simple and inexpensive patterns in the operation of casting said units.

Figure 1 is a top plan view of a 90° railroad crossing constructed in accordance with my invention.

Figures 2, 3, 4 and 5 are cross-sectional views, taken on the lines 2—2, 3—3, 4—4 and 5—5 of Figure 1; and

Figure 6 is a fragmentary top plan view on an enlarged scale, showing three of the members of the crossing separated slightly so as to more clearly illustrate the construction

of same and the way said members are connected together.

In the accompanying drawings which illustrate the preferred form of my invention, A designates what I will term the two main members of the crossing, which are arranged in parallel relationship with each other so as to form continuations of the rails of one track, and while I prefer to form each of the members A from a single casting, this is not

absolutely essential, for if desired, each of the members A could be composed of three sections separated by joints located at the flangeway openings of the intersecting track. The portions of the crossing that form continuations of the rails of the other track are formed by two intermediate members B arranged parallel and in spaced relation between the members A, and two pairs of end members C

arranged on the outside of the members A in longitudinal alignment with the intermediate members B. The various members A, B and C above referred to are constructed from cast metal and are detachably connected together, as hereinafter described. Said members are of substantially inverted channel shape in cross section, and each of said members comprises a pair of vertically-disposed

side legs 1, a horizontally-disposed web 2 integrally connected to said side legs, so as to form a wheel tread surface that is provided with a flangeway 3, and horizontally-disposed base flanges 4 that project laterally from the side legs 1 and which are adapted to rest upon the track ties or other supporting structure that sustains the crossing. The top portions of the main members A are provided with transversely-disposed grooves or flangeways 3^a that form continuations of the flangeways 3 in the intermediate members B

and end members C. As shown in the drawings, the outer ends of the flangeways in the main members A and in the end members C are flared at 4 so as to guide the flanges of the wheels into the flangeways of the crossing.

The main members A and the end members C are provided with reduced extensions, which are shaped so that the track rails can easily be connected to or detached from same, and after being connected to said extensions,

will be held securely against vertical movement by parts on said extensions which conform to the fishing section of the rails. All of the extensions above referred to are of the same construction, and each comprises a wheel tread part 5 of about one-half the width of the top web 2 of the member, that extends along one side of the head of the rail, and a depending, vertically-disposed leg 6 on said part that conforms approximately to the fishing section of the rail and laps over the base flange of the rail, as shown in Figure 2. If desired, the said depending part 6 can be provided with a plurality of ribs 6^a, shown in Figures 2 and 6, that are adapted to bear against the underside of one-half of the head of the rail and against the outside face of the web of the rail. By making the extension of less width than the member of which it forms a part, I produce a shoulder on said member against which the end of the rail abuts, thereby effectively preventing the rail from moving longitudinally in one direction relatively to the member to which it is attached, and by providing said extension with a part that projects into and conforms approximately to the fishing section of the rail, I effectively prevent vertical movement of the rail. As shown in Figure 2, the extension above described is provided with a plurality of holes for receiving bolts 7 that are used to connect the rail to the same, it being preferable to arrange an angle bar or fish plate 8 on the gauge side of the rail, as shown in broken lines in Figure 2, and have the bolts 7 pass transversely through the outside leg and part 6 of the extension, through the web of the rail, and through the angle bar 8.

The intermediate members B and the end members C are shaped so that they can be arranged in abutting relationship with the main members A, with portions of said main members disposed so as to prevent the intermediate members B and end members C from moving vertically either upwardly or downwardly. This feature of my invention is shown more clearly in Figures 4 and 6 of the drawings, wherein it will be noted that the members B and C are each provided with a vertically-disposed attaching flange 9 that bears against the side leg 1 of the member A and is securely clamped to said side leg by bolts or other suitable fastening devices 10. Said attaching flange 9 is made long enough so as to provide a bearing surface of considerable area on the member A, and said attaching flange is integrally connected to the side legs and to the top web of the member of which said flange forms a part. The lower edge of said attaching flange is also integrally connected to substantially triangular-shaped tie plate portions 11 that merge into the base flanges 4 of the member of which the attaching flange forms a part, the said tie plate portions 11 being slightly recessed on their undersides so

that they will lap over the adjacent base flange 4 of the main member A, as shown clearly in Figure 4. Holes 12 are formed in the tie plate portions 11 to receive tie spikes and the members A are provided with horizontally-disposed ribs or lateral projections 13 that lap over the attaching flanges 9, and thus co-operate with the base flanges 4 on the main members A to form pockets for the portions of the intermediate members B and end members C that butt against said main members. 70 75

By connecting the co-operating members of the structure together in this manner I produce a crossing that is strong enough to successfully carry the loads to which it is subjected, but which is more flexible than the conventional one-piece cast metal crossing. Such a crossing can be manufactured at a relatively low cost, because inexpensive patterns of simple design can be used in the operation of casting the various members from which the crossing is composed and an imperfection or defect in one member of the crossing does not destroy the entire crossing and cause it to be rejected, as is the case with a one-piece cast metal crossing, when a portion of same is defective. The component parts of the structure are easy to assemble or disassemble, and said parts are of such design that when they are combined, they mutually support each other in such a way as to overcome the necessity of using rail braces. The members A, B and C of the crossing have tie engaging surfaces of sufficient area to insure a firm bearing for the crossing on the support on which it rests, and the integral tie plate portions 11 of the members B and C overcome the necessity of using separate tie plates under the intersecting portions of the crossing. 90 95 100 105

If desired, the portions of the members A, B and C through which the bolts 7 and 10 pass can be reinforced and strengthened by integral internal lugs 7^a and 10^a in which the bolt holes are formed. External lugs 7^b and 10^b can also be formed on said members so as to form surfaces that co-operate with the heads of the bolts 7 and 10 to prevent the same from rotating when the nuts on said bolts are being tightened during the operation of connecting the rails to the crossing or during the operation of attaching the co-operating members of the crossing together. The main members A may also be provided with reinforcements, shown in broken lines in Figure 6 and designated as an entirety by the reference character 14, so as to strengthen the portions of said main members A to which the intermediate members B and end members C are attached. 110 115 120 125

Having thus described my invention, what I claim as new and desire to secure by Letters Patent is:

1. A railroad crossing, comprising a pair of main members that co-operate with the 130

rails of one track, each of said main members consisting of a casting of substantially inverted channel shape in cross section provided with laterally-projecting base flanges, 5 intermediate members and end members arranged at an angle to said main members so as to form continuations of the rails of the other track, integral attaching flanges on said intermediate and end members that bear 10 against the sides of said main members, tie plate portions on said intermediate and end members integrally connected to the attaching flanges of same and recessed so as to lap over the base flanges of said main members, 15 ribs or projections on said main members that lap over the top edges of said attaching flanges, and reduced extensions at the outer ends of said main members and end members to which the track rails are connected, said 20 extensions being constructed so as to prevent relative vertical movement between said extensions and the track rails.

2. In a railroad crossing, the combination of a main member and a second member arranged in angular relationship and each composed of a casting of substantially inverted channel shape in cross section whose side legs have laterally-projecting base flanges, a vertically-disposed attaching flange integrally connected to the end of said second member and arranged transversely of same in snug engagement with one side leg of said main member, and substantially triangular-shaped tie plate portions on said second member integrally connected to the base flanges and to the attaching flange of said member.

3. In a railroad crossing, the combination of a main member and a second member arranged in angular relationship and each composed of a casting of substantially inverted channel shape in cross section whose side legs have laterally-projecting base flanges, a vertically-disposed attaching flange integrally connected to the end of said second member and arranged transversely of same in snug engagement with one side leg of said main member, substantially triangular-shaped tie plate portions on said second member integrally connected to the base flanges and to the attaching flange of said member, 45 ribs at the upper end of said main member that lap over the top edge of said attaching flange, and a recess at the terminal end of said second member that is adapted to receive the base flange on the side leg of said main member which is engaged by said attaching flange.

ROBERT E. EINSTEIN.
